No. 712,629.

Patented Nov. 4, 1902.

D. ZATZKE.

WINDOW FRAME.

(Application filed July 3, 1902.)

(No Model.)

UNITED STATES PATENT OFFICE.

DANIEL ZATZKE, OF CHICAGO, ILLINOIS.

WINDOW-FRAME.

SPECIFICATION forming part of Letters Patent No. 712,629, dated November 4, 1902.

Application filed July 3, 1902. Serial No. 114,220. (No model.)

To all whom it may concern:

Be it known that I, DANIEL ZATZKE, a citizen of the United States, residing at Chicago, in the county of Cook and State of Illinois, have 5 invented certain new and useful Improvements in Window-Frames; and I do hereby declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to improvements in window-frames; and it consists in novel parts and combination of parts described herein-after and set forth in the claims.

In the drawings, Figure 1 is a front elevation. Fig. 2 is a section on the line 2 2 of Fig. 1, showing the frame only. Fig. 3 is a like view showing the panes in position. Fig. 4 is a section on the line 4 4 of Fig. 1, showing the frame only. Fig. 5 is a like view 25 showing the panes in position.

Referring more particularly to the drawings, the frame comprises a bottom rail 6, stiles 7, a top rail 8, a horizontal bar 9, and a vertical bar 10. The bars are constructed of 30 one piece, the horizontal bar passing through the bar 10 and into the stiles. By this construction the frame is greatly strengthened and the tendency to warp is lessened.

The frame formed as above described receives panes of glass, secured thereto in the following manner: The inside of the top rail 8 is rabbeted, as at 8^a, to receive the top of the upper panes of glass. The upper part of the stiles 7 and vertical bar 10 above the horizontal bar 9 are rabbeted, as at 7^a and 10^a, respectively, to receive the upper panes of glass. Similar rabbets 7^a and 10^a are formed 40 in the lower part of the stiles and vertical bar to receive the lower panes. The depth 45 of the rabbets is slightly greater at the bot-

tom than at the top, so that where they meet in the middle a shoulder 11 is formed, on which the lower edge of the upper panes rests and whereby they are supported. The shoulder is substantially the same width as 50 the thickness of the pane, and this construction permits the panes to overlap where they meet at the bar 9, the upper being outside to shed the rain. The lower edge of the lower panes is seated outside a bead 6^a, formed on 55 the lower rail 6, and putty may be applied at the outer lower edge, as indicated at 12. This is all the outside puttying that need be done to glaze the sash, the remainder being 60 inside, as at 13. It will be seen that by this construction the sash need not be removed in securing a pane to the same, and a neat and attractive window is obtained.

Having thus described my invention, what is claimed as new, and desired to be secured 65 by Letters Patent, is—

1. A window-sash the stiles of which are rabbeted interiorly to receive the panes, shoulders formed in the rabbets on which the upper pane rests, and an inwardly-presented 70 shoulder formed in the top rail, and an outwardly-presented shoulder in the bottom rail to retain the panes, substantially as shown and described.

2. A window-sash comprising top and bottom rails and stiles, a vertical bar extending between the top and bottom rails, and a horizontal bar extending between the stiles and through the vertical bar, the stiles having shoulders at the lower edge of the horizontal 75 bar, and upper and lower panes which lap 80 behind the horizontal bar, the upper panes resting on the shoulders, substantially as shown and described.

In testimony whereof I affix my signature 85 in presence of two witnesses.

DANIEL ZATZKE.

Witnesses:

NELLIE FELTSKOG,
H. G. BATCHELOR.
